CLAIM

The ornamental design for a support panel for use with waist traction belt, as shown and described.

DESCRIPTION

FIG. 1 is a front perspective view of a support panel for use with waist traction belt;

FIG. 2 is a front elevation view of the support panel for use with waist traction belt of FIG. 1;

FIG. 3 is a rear elevation view of the support panel for use with waist traction belt of FIG. 1;

FIG. 4 is a left-side view of the support panel for use with waist traction belt of FIG. 1;

FIG. 5 is a right-side view of the support panel for use with waist traction belt of FIG. 1;

FIG. 6 is a top plan view of the support panel for use with waist traction belt of FIG. 1; and,

FIG. 7 is a bottom plan view of the support panel for use with waist traction belt of FIG. 1.
